LOCOMOTIVE

Original Filed Nov. 20, 1929

UNITED STATES PATENT OFFICE

EDWIN ARCHER TURNER, OF NEW YORK, N. Y., ASSIGNOR TO THE STANDARD STOKER COMPANY, INCORPORATED, A CORPORATION OF DELAWARE

LOCOMOTIVE

Original application filed November 20, 1929, Serial No. 408,484, now Patent No. 1,829,425, dated October 27, 1931. Divided and this application filed October 24, 1931. Serial No. 570,810.

My invention relates to railway rolling stock and especially to improvements in the construction of stoker fired locomotives. This application is a division of my application Serial No. 408,484 filed November 20, 1929, Patent Number 1,829,425, granted October 27, 1931, for locomotive and tender.

The general object of the invention is the provision of a novel and improved construction of a stoker fired locomotive wherein the design is materially simplified, the weight reduced, the cost of construction and maintenance lowered and resulting in a more durable structure.

More specifically it is an object of the invention to provide in a locomotive, a main frame or a portion thereof having a stoker feed conduit formed therewith as an integral and unitary part.

On the drawing,

Fig. 1 is a detail central vertical longitudinal section through the rear portion of a locomotive with the fuel conduit thereof also shown in similar section; and

Fig. 2 is a transverse vertical section on the line 2—2 of Fig. 1.

In the drawing the locomotive A is equipped with a conventional boiler 10 having its component parts of conventional form. The frame structure of the locomotive is shown at 11. This structure may be made in the form of a unitary casting or the rearward portion of the frame structure here marked 11 may be regarded as illustrating the cradle casting sometimes constituting a part of the main frame structure. For purposes of illustration the reference character 11 designates generally the rear portion of the main frame structure of the locomotive and specifically the cradle casting thereof. A stoker fuel conveyor F is mounted on the locomotive for delivering fuel to the firebox 12 thereof. This conveyor comprises a conduit section 13 formed integrally with the main frame structure 11 and an upwardly extending replaceable delivery or mouth section 14. The replaceable section extends loosely into the firebox and is supported in the seat 15 in the forward curved portion of the integral conduit section. The screw sec-

tion 16 of the fuel conveyor terminates at or adjacent this curving portion and forces the fuel upwardly through the replaceable conduit section into the zone of action of the distributing blast issuing from the distributor head 17 acting to spread the fuel over the fire as is well known in practice.

The replaceable conduit section 14 is protected from the heat of the fire by an apertured protecting grate wall 18. This wall partially surrounds that portion of the replaceable conduit section that otherwise would be exposed to the heat of the firebox.

In forming the conduit section 13 of the fuel conveyor with the main frame structure or cradle casting 11, it is preferable that the conduit section be disposed as close to the frame as is permissible and that longitudinally extending laterally projecting tie members or ribs 19 be employed together with transversely extending ribs 20 to form a rigid and durable main frame or cradle casting having combined therewith a stoker feed conduit section.

Forming the conduit section integrally with the frame has the advantage of permitting the conduit to be placed close to or if desired depressed within the frame forming a compact arrangement and one wherein the conduit may occupy less space on the locomotive than in the constructions of past practice. This structure has the further advantage of eliminating undesirable loose connections and strengthens the rear portion of the frame structure.

I claim:

1. In a locomotive, a main frame structure having a stoker conduit section formed integrally with a part thereof, and longitudinally and transversely extending walls tying said conduit section to the aforesaid part of the frame.

2. In a locomotive, a frame structure having a stoker conduit section formed integrally with a part thereof, longitudinally extending walls inclined from the aforesaid part for tying said conduit section thereto, and spaced transverse ribs extending between said longitudinally extending walls.

3. In a locomotive, a frame structure hav-

ing a stoker conduit section formed integrally with a part thereof, longitudinally extending walls inclined from the aforesaid part for tying said conduit section thereto, and spaced 5 transverse ribs extending above said longitudinally extending walls.

4. In a locomotive, a frame structure having a stoker conduit section formed integrally with a part thereof, longitudinally extending 10 walls inclined from the aforesaid part for tying said conduit section thereto, and spaced transverse ribs extending below and above said longitudinally extending walls.

5. In a locomotive, a frame structure having 15 a stoker conduit section formed integrally with a part thereof, longitudinally extending walls inclined from the aforesaid part to the bottom of said conduit section for tying the same thereto, and spaced transverse ribs 20 extending below and above said longitudinally extending walls.

In testimony whereof I affix my signature.
E. ARCHER TURNER.
